(57) **CLAIM**

The ornamental design for a neck wrap, as shown and described.

DESCRIPTION

FIG. 1 is a front, right and top perspective view of a neck wrap, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof; and,

FIG. 8 is another front, right and top perspective view of the neck wrap in a usable state.

The broken lines shown in FIGS. 1-7 depict portions of the neck wrap that form no part of the claimed design. The additional broken lines in the form of a human head shown in FIG. 8 depict environmental subject matter and form no part of the claim thereof.
